UNITED STATES PATENT OFFICE

JOHN ERICKSON, OF CHICAGO, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

SWITCH MECHANISM

Application filed September 29, 1930. Serial No. 485,035.

The present invention relates in general to switch mechanisms, but is particularly concerned with the provision of a compact switch mechanism and of improved supporting means for holding a large group of such mechanisms.

One object of the invention is to provide a switch mechanism which may be operated at much higher speed than has been possible to attain in former switch mechanisms of a similar character.

Another object is to provide a switch which is very compact, but which may be readily disassembled for repair or inspection.

Still another object resides in the provision of a simplified mounting arrangement wherein the support for the switches simply consists of an I-beam upon both sides of which the switches may be readily mounted.

Another object is to provide a switch of the foregoing type which may be readily modified to operate spring combinations at any desired level or combination of levels of the wipers.

There are various other detailed features, not specifically mentioned, but which will be brought out in the description and claims which follow.

The invention is disclosed in six sheets of drawings which show various views of the switch mechanism as well as the means by which the same is supported.

Fig. 1 illustrates an upright having one switch mounted thereon with its cover in place, but with the switch banks omitted, and with a second switch base in place having its banks mounted thereon.

Fig. 2 is the top view of the switch support.

Fig. 3 is a view of the left side of the switch assembly shown in Fig. 1, with that part of its shaft which supports its wipers, broken away.

Fig. 4 is a view of the jack assembly as it appears when withdrawn from the switch base as illustrated in Fig. 3.

Fig. 5 is a rear view of that portion of Fig. 3 within which the jack assembly is mounted.

Fig. 6 is a sectional view of a portion of the base taken on line 6—6 of Fig. 1.

Figs. 7 and 7B constitute a front view of the switch mechanism with the portion designated Fig. 7C removed and shown immediately above its usual position in the assembly, and with the portion Fig. 7D removed and shown immediately to the right of its position in the assembly.

Fig. 8 is a side view of Fig. 7D; while Fig. 9 is a back view of this portion of the mechanism.

Figs. 10 and 10A, when placed together, illustrate a side view of the mounting frame portion of the mechanism illustrated in Figs. 7 and 7B.

Fig. 11 is a detail of the mechanism illustrating how the back stroke of the primary magnet armature is adjusted.

Fig. 12 is a view of the right side of the switch mechanism with that portion of the frame member shown in 7B broken away.

Fig. 13 is a rear view of the mechanism with that portion of the frame member shown in Fig. 7B omitted.

Figs. 14, 15, 16, and 17 are details of the level spring operating mechanism.

Fig. 18 is a top view of the switch, with the frame portion shown in Figs. 10 and 10A omitted.

Fig. 19 is a side view, with the frame portion shown in Figs. 10 and 10A omitted.

Fig. 20 is a bottom view, with the frame portion shown in Figs. 10 and 10A omitted.

Figs. 21, 22, 23, and 24 are details of the shaft and its operating mechanism.

Fig. 25 is a diagrammatic perspective illustration of the operative relation of certain of the details.

Fig. 26 illustrates a modified form of the mechanism; while Fig. 26A is a detail of this modified form.

Figs. 27 to 32, inclusive, are front, right side, back, top, left side, and bottom views, respectively, of the main frame member upon which all operating mechanism of the switch is mounted.

Referring now to Fig. 1, the support for the switch mechanism will be described. The support comprises an I beam 101 secured to the floor 100 by means of the brackets 103 and 103', Fig. 2, which are suitably riveted to the

I beam. The front and back surfaces of the I beam are perforated and tapped to receive screws 301 to hold the switch bases thereon. As will be seen from Fig. 1, each base employs four screws 301 to hold it on the support. The switch bases are insulated from the I beam by means of a sheet of fiber 102 placed intermediate to the I beam and the switch bases. The screws 301 are of the type disclosed in Obergfell et al., Patent No. 1,674,258, issued June 19, 1928, and the bases 109 are, therefore, fully insulated from the support.

The base 109 is made preferably of aluminum, although the same may be made of a compound such as bakelite. As will be observed from Fig. 6, the back portion is substantially flat, extra material, however, being molded into the portion surrounding the holes 201 to give added strength and to slightly reinforce the frame from the insulating strip 102, except at the points of fastening. Raised portions 178 on the inside of the base are provided to give the same added strength.

The opening 113 is provided for receiving the jack assembly shown in Figs. 1, 4, and 5.

The left side of the forwardly-extending portion of the base 109 is provided with a number of ribs 107, which are provided merely to strengthen the structure. On this portion of the base a switch locking spring 337 is mounted, by means of screws 303 and 304 threaded into perforations 203 and 204. The screw 304 limits the movement of the spring 337 to the right.

A pair of extensions 106' and 106² and having strengthening ribs 111 serve as supports for the switch banks. The frames of the banks themselves are bent over and have tapped perforations which align with the perforations 202 in members 106' and 106², and are firmly held in place by screws such as 305.

The jack assembly is made up of a number of units held between insulating combs 601 and 602, and they in turn by perforated plates 603 and 604. The screws 350 pass through the assembly and are threaded into the perforations in plate 604. The assembly, as a whole, is then slipped into the opening 113, the heads of the screws registering with notches in one side of the opening, and the other ends of the screws registering with notches on the other side of the opening. The nuts, such as 351, are then drawn up to hold the assembly firmly in place.

The switch frame structure is made up of a cast portion, machined, drilled, and tapped, as illustrated in Figs. 27 to 32, inclusive; and of a punched-out and formed sheet-metal portion as illustrated in Figs. 7, 7B, 10, and 10A. The pressed-out portion of the frame is secured to the cast portion thereof by four screws.

The sheet-metal portion of the frame has

its front portion, shown in Fig. 7B, properly perforated to receive the various relays and condensers required for use in the control of the switch. As illustrated, it is arranged to receive five relay assemblies and a condenser. The pressed-out portion, however, can be readily enlarged if more relay space is required.

Referring particularly to Fig. 13, it will be noted that a jack assembly 900 is bridged across the switch frame members 125 and 126 of the sheet-metal portion of the frame. This assembly is held in place by suitable brackets 901 and 902, respectively. All electrical apparatus of the switch is wired up to this jack assembly.

Two notches 903 and 904 are cut out of the upper portion 125 of the switch frame and like notches are also cut out of the portion 126 of the frame. These notches register with the pins 501 to 504 of the base when the switch is properly mounted thereon with the jack of the switch registering with the jack on the base. With the switch in proper position, the locking lug 337' on the switch frame snaps into a perforation in the previously-described locking spring 337, thereby locking the switch in place against accidental removal. To remove the switch, it is necessary to first withdraw spring 337 from lug 337'.

The line wiper assembly, as illustrated in Fig. 1, comprises a bracket 610' which is made of insulating material and held fast to the switch shaft 500 by the screw 351. The wiper assembly itself comprises wiper parts 333 and 334 which are tensioned towards each other. To make the assembly more rigid, a metal spacer 609 having insulation strips on each side thereof separates the two wipers 333 and 334.

The private wiper assembly is constructed in the same manner as the line wiper assembly, except that since there is plenty of room on the shaft, the holding bracket 610' is reversed and no insulating members are provided between the stiffening member 609 and the wipers. The eyelets 607 on the wipers are of a character suitable for holding tinsel wiper cords.

When the switch is wired up, the wiper cords are extended between the wipers and the wiper cord terminal block 910, shown in Figs. 7 and 20. The cords are then threaded into the slot connected opening 151 in the frame member so that they are less likely to become tangled up with the wipers during the operation of the switch.

Referring particularly to Figs. 7 and 25, the shaft-operating mechanism will be explained. In order to transmit a horizontal or primary movement to the shaft 500, the same is provided with a ratchet bar 610 held in place on the shaft 500 by nuts 375 and 376 threaded onto portions of the bar 610 which

extend through perforations in the shaft 500. A pair of primary magnets 378 and 379, appearing in Figs. 18 and 19, are mounted on the top of the frame over holes 208, shown in Fig. 30, in the same manner as are the magnets 385 and 386 of Fig. 13. A primary magnet armature 540 is held in pivoted relation to the frame 150 by a pin 501 passing through the armature and the frame and held firmly in place by the key 537, visible in Fig. 18. Adjusting screws like those shown in the top of the armature 545, of Fig. 13, are provided to regulate the air gap between the magnet cores and the armatures. These screws are held in any set position by a tension spring such as 330. As will be observed from Figs. 7 and 20, the free end of armature 540 is connected with an operating pawl 611 mounted in pivoted relation to the armature and held in engagement with the associated ratchet bar 610 by spring 329 extending between the armature 540 and pawl 611. In order to procure the proper backstroke adjustment of the armature 540, the arrangement illustrated in Fig. 11 is employed. An armature back-stop adjustment cam 612 is slidably wedged between the armature 540 and the incline 139' and is held in its adjusted position by a screw passing through the wedged member 612 and into a threaded perforation in the frame 150.

As illustrated in Fig. 20, the armature 540 is normally held against its back stop by a tension spring 320. This spring is one of a combination adjustably held between raised portions 152' and 152² on frame 150.

In order to definitely limit the forward movement of the pawl 611, a pawl-stop spring 662 is provided. This spring is secured at its lowermost end to the frame 150 by means of screw 663. An adjusting screw 664, passing through the frame member 150, is arranged to be drawn up against the tension of spring 662 to accurately adjust the extent of forward movement of pawl 611. A reduced portion of the screw 664 registers with a small perforation in the spring to hold the spring in perfect alignment.

Pivoted to the lug 181 of the frame 150 is a holding pawl 613 (shown in Figs. 7 and 20), secured in place by a shaft or pin 504 which in turn is held in place by the key 530. This holding pawl lies intermediate to the ratchet 610 and pawl 611 and is held against the surface of the ratchet teeth by a spring 328 having its left end connected to a portion of the holding pawl 613 and its right end secured to a pin on the upturned portion 548² of a release magnet armature 548.

Referring now particularly to Fig. 12, it will be observed that lying in the grooves of lugs 130, 136, and 128², is a shaft 505 upon which is mounted the assembly shown in Figs. 14 and 15, which will be described later, and which includes a shaft-restoring arm

614. As most clearly seen in Fig. 20, this shaft-restoring arm 614 has its free end tensioned against a bushing in the end of shaft 500 by a spring 327 extending from the pin 506 on arm 614 through the frame and held in place at the necessary tension by a key 644, illustrated in Fig. 19.

From the foregoing description, it will be obvious that upon energization of magnets 378 and 379 armature 540 will be attracted and will cause its pawl 617 to move the shaft 500 to the right one step. Upon completion of this movement, the holding pawl 613, under tension of spring 328, will drop into the tooth to the left and hold the shaft moved to the right one step.

Obviously, responsive to any number up to ten impulses will cause the shaft 500 to be moved to any of the intermediate or to the tenth position to the right against the tension of spring 327.

Mounted upon a raised portion of frame 150 and most clearly illustrated in Fig. 20, is a release magnet 615. The armature 548 of this magnet is connected in pivoted relation to the frame 150 by means of pin 616 which is keyed to the frame by the key 530'. The previously-mentioned extension 548² of this armature, it will be observed from inspection of Fig. 7, lies adjacent to the holding pawl 613 and at the upper side thereof. Therefore, upon energization of the release magnet, the armature extension 548² rotates the dog 613 clear of the ratchet teeth of the ratchet bar 610, and carries with it the operating pawl 611. When this occurs, the restoring spring 327 draws the arm 614 to the left to restore the shaft 500 to its normal position.

Other operations which take place in the course of the primary operation and release of the switch will now be explained. Upon energization of the primary magnets 378 and 379 and the consequent operation of the armature 540, the tension spring 320 encounters the bushing on contact spring 322 and separates this contact spring from the contact spring 321. Obviously, therefore, upon each energization of the primary magnets any circuit passing through the contact springs 321 and 322 will be momentarily interrupted.

Likewise, referring to Figs. 12 and 20, it will be observed that associated with restoring arm 614, there is a lever 617 pivoted to lugs on the frame 150 by means of the pin 507. The arm 619 on the lever 617 is engaged by an arm 614' of the lever 614 and is normally held toward the frame at this point so that the oppositely-disposed arm 618 normally maintains the contacts of springs 206 and 207 in engagement. However, upon the first movement of the shaft 500 responsive to the first impulse transmitted to the magnets 378 and 379, arm 614' disengages itself from

levers 617 permitting springs 206 and 207 to operate.

Also mounted upon the right side of the frame 150 and in pivoted relation thereto, is a lever 628. An extension 628¹ of this lever, shown in Fig. 7, lies in the path of movement of arm 548' of the armature 548, while an extension 628² is associated with the contact springs 208 and 209. Consequently, when the release magnet is actuated, the lever 628 also actuates and in turn actuates the contact springs 208 and 209 during the period of energization of the release magnet. Obviously, when the shaft restores to its normal position, the contact springs 208 and 209 which were operated upon the off-normal movement of the shaft, are again restored to their normal position.

As will be observed from the dotted line in Fig. 12, Figs. 14 and 15 represent two portions constituting the assemblies which are carried by the pin 505, but with the spring combinations removed to avoid unnecessarily complicating the drawings. The level spring mechanism support 619' is secured in fixed relation to the switch frame by the screw 399 and its associated washer 401, the screw passing through the slotted portion 620 of support 619'. The opposite end of this support has perforated ears 630 and 631 through which the shaft 505 passes. With this arrangement, the support 619' also serves to hold the shaft 505 solidly in fixed relation in the notches of the respective lugs 130, 136, and 128⁴. Mounted upon the support 619', are two spring sets comprising springs 301, 302, and springs 301', 302', respectively. To operate these spring sets, a pair of gear-driven cams 625 and 626 are provided. The cam 626 is secured in fixed relation to a flange 634 on sleeve 529 by screws 380 passing through the flange, cam, and into threaded perforations in a cylindrical spacer 632. On the opposite side of the spacer 632 is secured the cam 625 by means of screws 381. On the end of the sleeve 529 opposite to the one provided with the flange 634 is secured a pinion 621. A sector 622 has teeth cooperating with pinion 621 and is held in fixed relation to the shaft-restoring arm 614 by having an arm 614¹ wedged between a projecting member 622' and a clock spring 333 riveted to the sector 622. The sector 622 is at the same time mounted in pivoted relation to the pin 505 which passes through ears 622⁴ of the sector. Each spring combination is provided with an operating arm 627 pivoted to the pin 505 and having its free end equipped with a roller acted upon by the associated cam to actuate the spring combination.

From the foregoing it will be seen that upon operation of the shaft-restoring arm 614 the teeth on sector 622 will rotate the pinion 621 a distance dependent on the number of impulses transmitted to the magnets

378 and 379. Furthermore, as will be observed, the spacing member 632 having ten threaded perforations, enables the cams 625 and 626 to be set at any desired position with respect to the pinion 621 so that the spring combinations controlled by these cams may be operated at any desired position, or positions, of the shaft 500. Also if both combinations are to be changed as a unit, the sector may be withdrawn clear of the pinion and the pinion position readjusted with respect to the sector. For example, if the spring combinations are set to operate in the seventh and eighth positions and it is desired to change them to operate in the fifth and sixth positions, the sector is withdrawn clear of the pinion and the pinion rotated the proper distance in the proper direction and the sector returned into operative relation to the pinion.

Circuit arrangements with which switch mechanisms of this type are used in many instances do not require the level spring operating mechanism just described. Under such circumstances the assembly is omitted and a short pin similar to 505, but only reaching from lug 128⁴ to lug 136 need be employed. With this arrangement, the tension of spring 327 alone is ample to hold the arm 614 and the shorter pin in place on the assembly.

The operations which normally occur subsequent to the horizontal or primary setting of the shaft 500 will now be gone into. In the ordinary operation of the switch, following the primary movement of the shaft, produced to bring the wiper sets opposite a desired group of bank contacts, the shaft is rotated from one to eleven steps depending upon the number of impulses transmitted, either directly or automatically, by the rotary magnets 385 and 386. These magnets are secured to a shelf in the frame 150 by screws 635 and 636 passing through perforations 209 and threaded into openings in the cores of the magnets 385 and 386 in the usual manner. Intermediate to the frame 150, and the cores of the magnets 385 and 386 are double-hole washers 635' and 636'. Washer 636' simply serves as a spacer, while 635 is of magnetic material and serves as a magnetic yoke between the two magnet cores. The armature 545 is pivotally secured to the frame 150 immediately above the magnets 385 and 386 by a pin 501 held in place by a key 534. The armature 545 is provided with pole-adjusting parts identical to those on the armature 540 of the primary magnets.

As will be observed in Fig. 12, the free end of armature 545 has pivoted to it an operating pawl 637 tensioned into operative relation to the ratchet wheel 640 by a spring 320 extending from an eyelet on the pawl to an eyelet on the extreme end of the armature 545. Near the free end of the armature 545, a pin 509 also is provided. Adjacent this pin

and passing through the upper part of the frame 150 is an adjusting screw 302 which cooperates with the pin 509 to determine the back stroke of the armature 545. On the opposite side of the pin 509 is a tension spring 303 properly tensioned to hold the armature against its back stop. The tensioned spring 303 and contact springs 304 and 305 are mounted on a bracket 642 adjustably held 10 between raised portions 142' and 142² of the frame 150. Obviously, whenever the magnets 385 and 386 are energized, the armature 545 is drawn toward the magnet pole pieces with the results that pin 509 actuates against the 15 tension of spring 303 and through the medium of the bushing on spring 305 interrupts the contacts of springs 304 and 305 during the period of energization of the magnets 385 and 386.

20 The forward movement of the rotary pawl 637 is accurately determined by a slidable pawl stop 667 slidable in the groove 146 and held in any desired position by the holding screw 668, as shown in Figs. 7, 12, and 27.

25 From observation of Figs. 7, 12, and 25, it will be noted that as the shaft 500 is rotated the rack 610 is rotated clear of the pawls 611 and 613. To prevent the shaft 500 restoring when the pawls 611 and 613 are 30 cleared, the circular portion 680 on plate 700 is provided. Upon the first rotary step of the shaft 500, a tooth of the rack rides onto the rotary portion 680 and upon the second step it clears the pawls 611 and 613. Obviously, therefore, the pawl 611 merely functions to prevent retrograde movement of the shaft 500 prior to the transmission of rotary motion to the shaft.

35 The pawl 637 transmits rotary motion to the shaft 500 through the medium of the ratchet wheel 640, specific details of which are illustrated in Figs. 21 to 23, inclusive. The ratchet wheel 640 fits over the shaft 500 and is keyed thereto by the rack 610 passing 40 through a notched-out portion 643 of the ratchet wheel. A knurled member 645 has a notched-out portion 650 passing through a portion of the frame member 150 and is secured in fixed relation thereto by the nut 583. The spring 350, enclosed in a hollow 45 portion of the ratchet wheel 640 has its outside end bent over the outer wall of the ratchet wheel structure, while its inner end has a button 649 thereon which slides into the notch 650 of the knurled member 645 when the devices are properly assembled. A cover 651 fits into the opening in ratchet wheel 640 to assist in holding the spring 350 in place.

50 With this arrangement, by simply loosening the nuts 383, the knurled member 645 may be rotated to tension the spring 350 to any degree desired or found necessary to restore the shaft to its normal position, with respect to its rotary position after having been moved around 55 to any of its rotary off-normal positions,

and the lock nut 383 again tightened up. Mounted on a pin 536 in the upper forward part of the mechanism, having reference to Figs. 7 and 12, is a holding pawl 655 having its free end tensioned against the teeth of ratchet wheel 640 by the associated spring 326, which extends between pawl 655 and pin 701 on plate 700. This pawl has a forwardly-extending member 655', the purpose of which will be explained later. 75

Also mounted upon the pin 536 is a comb member 653 having an upwardly-extending spring-operating pin 647.

The rotary off-normal and eleventh contact cam spring combination illustrated in Fig. 7C, when in place in the upward-forward portion of the frame member 150, is placed under control of the spring-operating member 647. As will be seen from Fig. 18, 80 the finger 652 of the spring-holding bracket extends down between springs 315 and 316. The springs 316 to 319, inclusive, are rotary off-normal springs, while the springs 309 to 315, inclusive, are operable upon the eleventh 85 rotary step.

Referring now to Figs. 7 and 21, it will be observed that a lever 657 is secured to the underside of comb 653 by the screws 384. This lever is normally acted upon by the tension of spring 350 in the ratchet wheel. The cam 568 on wheel 640 normally holds the spring-operating member 647 against the spring 316 with sufficient force to overcome its tension and, therefore, holds the spring combination in the position shown in Fig. 18. 95

Upon the first rotary movement of the shaft 500, cam 568 is carried away from lever 657 and, consequently, the spring 316 functions to move its spring combination. Since, however, the finger 652 extends down between springs 315 and 316, none of the springs 309 to 315 are affected by the movement of springs 316 to 319. This is further guarded against by the semi-circular portion of lever 657, being brought near the inner surface of the cam 568 which positively limits the possible distance of rotation of spring-controlled member 647. 105

When the shaft has been rotated ten steps, 110 the lower end of lever 657 clears the extreme right edge of cam 568 rendering the spring-operating lever 647 free to be operated a greater distance than heretofore. When the shaft is rotated the eleventh step, pin 660 on the rack 610 encounters one of the teeth on comb 653 and in so doing rotates the comb a sufficient distance to cause the spring-operating member 647 to operate the spring combination comprising springs 309 to 315, 115 inclusive. 120

When certain groups of contacts are selected it may be desirable to prevent the operation of the cam springs. In such instances it is only necessary to break off the proper 130

tooth out of the comb 653 so that the pin 660 cannot move the comb on the eleventh rotary step of the shaft.

The manner of bringing about the restoration of the shaft 500 consequent to the operation of the release magnet, following the longitudinal movement of the shaft, has heretofore been explained. Referring now particularly to Figs. 7, 7D, 8, 9, and 12, the manner of causing the shaft 500 to release to its normal position after longitudinal and rotary movement thereof, will be gone into. The plate 700 when in place, as illustrated in Fig. 12, carries a link member 710 slidably secured to plate 700 by means of rivets 708. The link 710 has two rectangular openings 706 and 706' which register with the larger rectangular openings 704 and 704' in the front of plate 700. The extension 655' of the rotary holding pawl 655 passes through the openings 706 and 704, while the extension 548' of armature 618 of the release magnet passes through the openings 706' and 704'. The opening 706 is made considerably larger than the extension 655' in order to permit the movement of pawl 655 as it rides over the teeth of the ratchet wheel 640 without moving the link 710.

However, upon energization of the release magnet, armature 548, in actuating, through the medium of the extension 548' and the link 710, moves the holding pawl 655 clear of the ratchet wheel, thereby permitting the spring 800 to return the shaft to its normal rotary position. When it reaches this position it clears the circular portion 680 of plate 700, and since the pawl 657 and dog 655 are at this time held clear of the teeth on the rack 610 by the extension 548' of armature 548, the shaft is free to move to its normal position.

In the switch as described, the contact spring combination comprising springs 208 and 209 are actuated upon energization of the release magnet, and are restored upon restoration of the armature of the release magnet. Therefore, the circuits employed in connection with the switch, when constructed in this manner, are usually arranged to insure that the release magnet will remain energized until the switch shaft 500 has fully restored to its normal position.

In Figs. 26 and 26A a slightly modified form of the switch releasing mechanism is illustrated. In the modified form, the armature 549 of the release magnet has a locking arm 549' which cooperates with a locking spring 801. When the switch shaft is stepped off-normal, the arm 802 actuates the off-normal spring combination in the same manner as done by arm 617 in the former arrangement. At the same time, the arm 802 in addition moves clear of spring 801, but the release magnet spring combination does not actuate because the arm 549' is in the path of move-

ment of spring 801. When the release magnet is operated and the armature 549 thereof attracted, the locking arm 549' is brought in register with the opening 803 in spring 801 and, accordingly, the spring 801 moves toward the frame and permits the associated spring combination to operate. The release magnet may be deenergized immediately as the armature 549 is now held in its operated position by the spring 801. As the shaft assumes its normal position, the arm 802 restores the off-normal springs to normal position and at the same time moves the spring 801 clear of arm 549', thereby permitting the armature 549 to restore to its normal position.

What is claimed is:

1. In a switch mechanism, a supporting frame, a shaft having bearings in said frame, means for transmitting endwise movement to said shaft, sets of contact springs having associated cams for operating them, and means operative consequent to the endwise movement of said shaft to rotate said cams and thereby operate said springs.

2. In a multi-position switch, sets of bank contacts, wiper sets having access to said contact sets, a plurality of contact spring combinations, means for actuating said spring combinations at selected settings of said wiper sets, and means for changing the setting of one or any number of said spring-actuating means to operate at other desired settings of said wiper sets at will.

3. In a switch mechanism wherein a shaft is operated in a primary direction and then in a secondary direction to position its wipers into electrical connection with a specified set of bank contacts, a contact spring assembly comprising a bracket having sets of contact springs and having spring operating cams thereon, and means for readily securing said assembly in operative relation to said switch to enable the switch to operate said contact spring sets incidental to specified movements of the switch wipers.

4. In a switch structure having a multi-position rotatable shaft, a contact spring combination, means for operating certain of the springs of said combination consequent to the rotation of said shaft a limited distance and other means operative consequent to further rotation of said shaft to cause said first means to also move other springs of said combination.

5. In a switch structure having a multi-position rotatable shaft, a contact spring combination, means for operating certain of the springs of said combination consequent to the rotation of said shaft a limited distance, and other means operative consequent to a specific distance of further rotation of said shaft to cause said first means to also move other springs of said combination in certain instances.

6. In a switch mechanism, a frame, an

armature pivoted to said frame, a pin on said armature for operating associated contact springs also mounted on the frame, and an adjusting screw passing through a portion of said frame cooperative with said pin to adjust the back stroke of said armature.

7. In combination, a jack assembly where-in the elements of the jack are held together by screws which extend appreciably through the elements, receiving means for the jack assembly one side thereof having notched-out portions for receiving the heads of the screws and the side thereof having notched-out portions for receiving the free ends of the screws, and nuts threaded on said screws and drawn against said jack receiving means to frictionally hold said jack assembly in place.

10 8. In a switch mechanism, a frame, a shaft on said frame, means for operating said shaft, and a spring and cooperating arm for restoring said shaft, said spring and arm pivotally secured to said frame by the tension of the spring.

15 9. In a switch mechanism, a frame, a shaft protruding through one wall of said frame, a set of wipers on said shaft on one side of the wall, a terminal block on said frame located on the other side of the wall, said wall having an opening therein having a restricted portion extending through the extreme edge of the wall to enable wiper cords to be threaded into or out of said opening after the cords have been secured to the wipers and block respectively.

20 10. In a switch structure, a switch base comprising a back portion and a switch bank holding portion arranged parallel to each other and with a connecting portion lying at right angles to said parallel portions, a switch mechanism assembly slidably into said base, and means for automatically locking the switch mechanism and base together consequent to the placing of said mechanism in a predetermined position with respect to said base.

25 11. In a switch and base assembly, a jack and a set of contact banks on the base upon which incoming connections may be terminated, a jack and wiper set on the switch upon which outgoing connections may be terminated, means for removably holding said switch and base into juxtaposition to each other with the jacks of the switch in register with each other and the wiper sets in operative relation to the contact banks, and means for automatically locking the switch and base together consequent to the placing of said switch and base in such position with respect to each other.

30 12. In combination, a vertical member, switch bases mounted one above another on either or both of two sides of said member, switch contact banks and jack assemblies on said bases, switch mechanisms removably mounted on said bases and having wipers co-

operating with the contacts of said contact banks and jacks registering with the jacks on said bases.

13. In an electromagnetically operable switch of the type having a shaft adapted to be driven by a pawl and ratchet mechanism in a primary direction by one magnet and then in a secondary direction by a second pawl and ratchet mechanism and a second magnet, a movable pawl for holding said first ratchet in any position to which it is operated in its primary movement, means operative consequent to the secondary movement of the shaft for moving the first ratchet clear of said movable pawl, a fixed member for holding the first ratchet and encountered by said ratchet consequent to the secondary movement of the shaft, a second movable pawl for holding the second ratchet in any position to which it has been advanced, and means including a link connection between said movable pawls for permitting the shaft to restore to its initial position.

35 14. In an electromechanical switch having a shaft, pawl and ratchet mechanisms for moving said shaft in a step-by-step manner endwise and then rotating it in like manner, independently movable pawls for preventing retrograde movement of the shaft, a fixed element for preventing endwise movement of the shaft while the shaft is in a rotary off-normal position, a release magnet having a release armature coacting with said pawl and ratchet mechanisms, when said armature is held in its operated position, to clear the pawls of said mechanism from their ratchets; means then operative to restore the shaft to its non-rotated position clear of said fixed element, and means for then restoring said shaft to its initial endwise position.

40 15. In a switch mechanism, a shaft, means for moving said shaft in a primary direction, sets of contact springs, means operative consequent to the movement of said shaft for operating one set of said springs and for preparing the other set for operation, an element operative to bring about the operation of the prepared spring set and the restoration of said shaft, means for locking said element in its operated position until the shaft has substantially fully restored, said shaft being operative during the final portion of its restoring movement to cause the first-mentioned means to restore the said element and both spring sets.

45 16. In a switch mechanism, a shaft, means for moving said shaft in a step-by-step manner in a primary and then in a secondary direction, sets of contact springs, means for actuating one set consequent to the initial primary movement of said shaft, means for operating a second set each time the shaft is moved in the primary direction, means for operating a third set consequent to a predetermined primary movement of said shaft,

- means for operating a fourth set consequent to the initial secondary movement of said shaft, means for operating a fifth set each time the shaft is moved in a secondary direction, and means for operating a sixth set of said contact springs consequent to said shaft being operated in a secondary direction beyond a predetermined distance.
17. In a switch mechanism, a shaft, pawl and ratchet mechanisms for moving said shaft in a primary and secondary direction respectively, independently movable pawls for holding said shaft against retrograde movement, springs for restoring said shaft to its initial position, and an element for holding said pawls out of operative relation with said shaft to enable said springs to function.
18. In a switch mechanism, a shaft, a rack and ratchet wheel respectively secured to said shaft, an operating pawl associated with the rack, an operating pawl associated with the ratchet wheel, holding pawls between the rack and ratchet wheel and their operating pawls, one means for moving the holding and with it the operating pawl for the rack, and other means operative by said one means to also clear the other holding and operating pawl clear of the ratchet wheel.
19. In a switch mechanism, a shaft, a rack secured in fixed relation to said shaft, a ratchet wheel keyed to said shaft with the shaft slidable thereon, an operating pawl for operating said shaft through the medium of its rack, a pawl for holding said shaft in any position to which it is moved by said operating pawl, a fixed member for holding said rack, a second operating pawl cooperative with said ratchet wheel to rotate said shaft and to rotate said rack into cooperative relation with said fixed member and the rack clear of its operating and holding pawls, means for restoring said shaft to its initial position, and means for holding said operating and holding pawls clear of the rack and ratchet wheel while the shaft is restoring.
20. In a switch mechanism, a supporting frame, a pair of magnets mounted upon a shelf portion of said frame, an armature for said magnets having a supporting shaft passing through other portions of said frame and a key passing through the armature shaft and secured to said frame to hold the shaft in fixed relation to but readily removable from said frame.
21. In a switch mechanism, a frame, a shaft having a ratchet wheel thereon, a pawl for operating said shaft through the medium of said ratchet wheel, a circuit switching spring combination, a second shaft carrying a holding pawl cooperative with said ratchet to prevent retrograde movement thereof, an element also carried by said second shaft normally preventing certain springs of said combination from operating under their own tension, a lever carried by said second shaft cooperative with a cam on said ratchet wheel to hold the element in its normal position until the first shaft has been operated, and other means carried by said shafts cooperative with each other to cause said element to actuate the remaining springs of the combination during a subsequent movement of the first shaft.
22. In a wiper assembly, a wiper holding bracket made of insulating material and having a hole therein for receiving a shaft, means for frictionally holding said bracket to said shaft, and a wiper assembly having a hole therein of a greater diameter than is the hole in the bracket, the hole in said wiper assembly being in register and concentric with the hole in said bracket.
23. In a switch mechanism wherein a shaft equipped with contact wipers is first moved endwise and then in a rotary direction to selectively position its wipers, the combination of an associated shaft, with means for rotating it during the endwise movement of the first shaft, and groups of contact springs variably operated in accordance with the endwise movement of the first shaft by cams rotated by the second shaft.
24. In a switch mechanism wherein a shaft equipped with contact wipers is first moved endwise and then in a rotary direction to selectively position its wipers, the combination of an associated shaft, with means for rotating it during the endwise movement of the first shaft, a plurality of spring sets each having an operating cam, and means for readily changing the position of any cam with respect to the second shaft to cause the operation of its spring sets to occur at a different endwise position of the first shaft.
25. In a switch mechanism, a spring assembly comprising a bracket upon which the springs are mounted and having a finger separating the assembled springs into two groups, a shaft for the switch with mechanism for rotating the shaft, a lever actuated by the initial rotary movement of said shaft enabling the actuation, under their own tension, of the springs of one of said groups a distance limited by said finger, and other means associated with said shaft co-operating with said lever to actuate the said springs of the other group upon a subsequent rotation of said shaft.
26. In an electro-magnetic switch wherein a shaft is first moved endwise a limited number of steps by step-by-step mechanism and is then rotated a limited distance, the provision of a set of contact springs, a comb member having a number of teeth each of which is individual to a specific endwise position of the shaft and having an arm engaging and operating said springs each time the comb is operated, and an element on the shaft engaging the tooth of the comb which is individual to a specific endwise position of

said shaft to move the comb upon rotation of the shaft its limited distance, those teeth of the comb which are individual to specified endwise positions of the shaft at which the 5 springs should not be operated being broken away.

In witness whereof, I hereunto subscribe my name this 26th day of September, A. D. 1930.
